The ornamental design for a drone, as shown and described.

DESCRIPTION

FIG. 1 is a front, right and top perspective view of a drone, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 1; and,

FIG. 11 is a partial enlarged view of an area labeled 11 in FIG. 1.

The broken lines shown in the drawings are included for the purpose of illustrating portions of the drone that form no part of the claimed design.

In addition, the dot-dash broken lines in FIGS. 1, 9, 10, and 11 are for annotating the enlargements and form no part thereof.
